Primary Examiner — Paula Allen Greene*(74) Attorney, Agent, or Firm* — Kratz, Quintos & Hanson, LLP(57) **CLAIM**

The ornamental design for an earphone, as shown and described.

DESCRIPTION

FIG. 1 is a perspective view of an earphone showing our new design;

FIG. 2 is a front view thereof;

FIG. 3 is a rear view thereof;

FIG. 4 is a top plan view thereof;

FIG. 5 is a bottom view thereof;

FIG. 6 is a right side view thereof; and,

FIG. 7 is a left side view thereof.

The broken lines depict portions of the earphone that form no part of the claimed design.

1 Claim, 7 Drawing Sheets(56)
